UNITED STATES PATENT OFFICE.

GEORGE W. ECKERT, OF BUTLER, KENTUCKY.

ADJUSTABLE SCREEN.

1,211,560.

Specification of Letters Patent.

Patented Jan. 9, 1917.

Application filed January 8, 1916. Serial No. 71,071.

To all whom it may concern:

Be it known that I, GEORGE W. ECKERT, a citizen of the United States, residing at Butler, in the county of Pendleton and State of Kentucky, have invented certain new and useful Improvements in Adjustable Screens, of which the following is a specification.

This invention has relation to certain new and useful improvements in adjustable screens and has for its primary object, the provision of a screen of this character which will be of simple construction and may be readily adjusted in either direction.

The invention has for another object, the provision of a screen of this character which may be formed of corner sections adjustably and slidably mounted upon one another.

The invention has for a further object, the provision of a screen of the above stated character which will be composed of the minimum number of parts and in which the outer frame members of the corner sections may be constructed for telescopic engagement with one another to form the outer sides and ends of the screen.

The invention has for a still further object, the provision of a screen of this character in which will be provided means for readily securing the wire mesh carrying frames to the main frame members of the corner sections.

With the above and other objects in view, the invention resides in the novel construction, combination and arrangement of operating parts as hereinafter more specifically set forth, pointed out in the claims and shown in the drawings, in which:

Figure 1 is an elevation of the complete window screen, Fig. 2 is a detail section substantially on the plane of line 2—2 of Fig. 1, Fig. 3 is a detail sectional view substantially on the plane of line 3—3 of Fig. 1, Fig. 4 is a detail section, substantially on the plane of line 4—4 of Fig. 1, Fig. 5 is a detail section, substantially on the plane of line 5—5 of Fig. 1, Fig. 6 is a detail section, substantially on the plane of line 6—6 of Fig. 1, Fig. 7 is an elevation of the removable wire mesh frame employed in this invention, and Fig. 8 is a detail section on the plane of line 8—8 of Fig. 7.

Referring more particularly to the drawings, in which similar reference characters designate corresponding parts throughout the several views, 1 designates a wire mesh carrying frame which is formed of suitable

metallic strips composing the sides and ends of the frame and having their opposite edges bent back, as shown at 2, to form gripping means for the edges 3 of the wire mesh body 4, the edges of the wire mesh body 4 being clamped in the strips forming the frame 1, as clearly shown in Fig. 8. The frame 1 is provided with suitable openings 5 in its upper and lower ends and in one side, to receive securing members as will be later clearly apparent. It will also be understood that the ends of the strips forming the frame 1 are suitably beveled and secured together, as shown at 6 to form the corners of the frame. The frame is also preferably of rectangular form and in constructing the complete screen, I desire to employ four wire mesh carrying frames 1, one wire mesh carrying frame 1 being necessary for each corner of the screen.

Each corner of the screen is composed of an outer horizontal member 7, an outer vertical member 8 and an inner horizontal member 9 parallel with the member 7. For the purpose of making the interlocking adjustment of the sections of the screen clear, I have marked the four sections A, B, C and D respectively. As shown in the drawings the section A forms the lower right hand corner of the complete screen and the section B forms the lower left hand corner while the sections C and D form respectively the upper right and left hand corners of the complete screen.

The outer horizontal member 7 of the corner section B has its bottom 10 flattened and slidably engaged in the portion 11 of the member 7 of the corner section A, it being understood that the sections have their outer members 7 and 8 formed of hollow metallic sleeves bent as clearly shown in Figs. 2 to 4 inclusive. The sides of the member 7 of the section B are then brought together to form the web portion 12 enclosed in the web portion 13 of the member 7 of the section A, as clearly shown in Fig. 2. The sides of the web portions 12 and 13 of the members 7 are then bent outwardly at right angles and then again bent toward one another to form the flared portions 14 and 15 which cooperate with the portions 10 and 11 to retain the sections A and B in proper position in relation to one another. One edge 16 of the member 7 of the section B is then extended and provided with suitable right angled frame holding lugs 17 upon one

face. The opposite edge 18 of the member 7 of the section A is also extended parallel with the edge 16 of the first mentioned member 7 and also carries on one face the frame holding lugs 19. The outer horizontal members 7 of the sections C and D correspond in practically every particular with the outer horizontal members 7 of the sections A and B respectively and the foregoing description 10 of these parts of the sections A and B will also serve as a correct description of the parts mentioned of the said sections C and D and therefore further description of the construction and telescoping engagement of 15 these parts of the sections C and D will be unnecessary.

The outer vertical members 8 of the sections A and B are constructed in the same manner as the parts or members 7 and will 20 therefore be numbered the same as the members 7. It may also be stated that the outer vertical members 8 of the sections A and B are of the same size to receive the reduced outer vertical members 8 of the upper corner sections C and D, as will be readily understood by referring to Fig. 1 of the drawings. It will also be seen by referring to Fig. 1, that the diagonally opposite screen sections B and C are provided each with a 25 large outer member and a small outer member, the outer member 8 of the section B being large while the outer member 7 of the section C is large and the remaining outer members of said sections B and C being small for sliding engagement respectively in the members 7 and 8 of the section A. Therefore the members 7 and 8 of the section A are both large while both of the outer members 7 and 8 of the diagonally 30 opposite section D are small for sliding engagement respectively in the outer members 7 and 8 of the sections C and B. By this arrangement and interlocking of the corner sections of the screen, the latter may 35 be readily adjusted in either vertical or horizontal directions to suit the window frame or door frame in which it is to be positioned.

By referring to Figs. 3, 4 and 6, it will be 40 seen that the extended edges 16 and 18 of the members 7 and 8 have their frame holding lugs 17 and 19 formed by bending outwardly and offsetting portions of said edges and certain of these lugs 17 and 19 are provided with suitable openings 20 for the 45 threaded securing members 21 adapted to be engaged through the same and through the openings 5 in one end and one side of the several wire mesh carrying frames 1. Each securing member 21 is also adapted to be extended through an upper washer 22 and 50 threaded in a lower washer 23 engaged against the face of the extended edge opposite that against which the frames 1 are secured. This should be readily understood 55 by referring to Fig. 6 of the drawings. The

remaining end of each wire mesh carrying frame 1 is similarly clamped against one face of the extended edge 24 of the member 9 of the screen section by which said frame 1 is carried by means of the clamping lugs 70 25 mounted upon said extended edge 24. By referring to Fig. 5 of the drawings, it will also be readily seen that the overlapping members 9 of the lower screen sections A 75 and B are bent to form V-shaped channels 26 which are engaged one in the other for transverse or horizontal adjustment of the screen. It will also be understood that the inner horizontal members 9 of the upper corner sections C and D are similarly formed 80 to assist in the transverse adjustment of the screen. During longitudinal or vertical adjustment of the screen however only movement of the outer vertical members 8 within one another will be necessary. 85

From the foregoing it will be seen that the inner vertical edge of each wire mesh carrying frame 1 is free and each frame may be readily moved to proper position within the clamping members 19 or withdrawn from the same when the corner screen sections are separated. It will also be seen that the corners of the screen are reinforced by suitable corner bracing members 27 secured in the outer corners of the corner screen sections A, B, C and D and having arms 28 extending over and secured to the extreme corners of the screen while the oppositely directed arms 29 extend toward the center of the screen and have the feet 30 90 formed on their inwardly bent ends and secured in the curved channel bars 31 which extend over the corners of the wire mesh carrying frames 1 and have their opposite ends connected with the members 7 and 8 95 of said corner screen sections, as will be readily seen by referring to the drawings. This forms a secure bracing means for the corners of the adjustable screen and gives 100 the same a finished appearance. 105

While the preferred embodiment of the invention has been shown and described minor changes in the details of construction and arrangement of parts may be resorted to within the scope of the appended claims without departing from the spirit of the invention without sacrificing any of the advantages of the same. 110

I claim:

1. An adjustable screen comprising interlocking hollow corner members and overlapping wire mesh carrying screens mounted upon said corner members. 120
2. An adjustable screen comprising hollow corner members including upper and lower horizontal frame members, vertical frame members connecting said horizontal frame members, and independent wire mesh carrying frames mounted upon said frame members. 125

3. An adjustable screen comprising vertical and horizontal adjustable hollow frame members, and overlapping wire mesh carrying frames mounted upon said frame members. 40
4. An adjustable screen comprising upper corner members mounted upon one another for transverse adjustment, lower corner members mounted upon one another for transverse adjustment, the corresponding upper and lower corner members being mounted upon one another for vertical adjustment, and independent overlapping wire mesh carrying members mounted upon said corner members. 45
5. An adjustable screen comprising upper and lower corner members telescopically connected for vertical adjustment upon one another, the corresponding upper and lower corner members being telescopically connected for horizontal adjustment upon one another, and wire mesh carrying frames mounted upon the separate corner members. 50
6. An adjustable screen comprising four corner members telescopically connected for horizontal and vertical adjustment of the screen, an independent wire mesh carrying frame for each corner member, said wire mesh carrying frames being adapted for overlapping engagement, and means for securing said wire mesh carrying frames in position upon said corner members. 55
7. An adjustable screen comprising upper corner members mounted upon one another for transverse adjustment, connected lower 60
- corner members mounted for longitudinal adjustment upon said upper corner members, and overlapping wire mesh carrying screens mounted upon said corner members. 65
8. An adjustable screen comprising corner members having hollow horizontal and vertical outer frame members, the hollow outer frame members of said corner members being telescopically connected to permit transverse and longitudinal adjustment of the screen, interlocking inner horizontal frame members for said corner members, and means for bracing said corner members. 70
9. An adjustable screen comprising corner sections including outer horizontal and vertical hollow frame members and inner horizontal frame members, the outer horizontal and vertical hollow frame members being telescopically connected to provide for transverse and longitudinal adjustment of the screen, the inner horizontal frame members of the lower corner sections being interlocked, the inner horizontal frame members of the upper corner sections being interlocked, a wire mesh carrying frame for each corner section, means for securing each wire mesh carrying frame in position upon the proper corner section, and bracing means for the outer corners of said corner sections. 75

In testimony whereof I affix my signature 80
in presence of two witnesses.

GEORGE W. ECKERT.
